UNITED STATES PATENT OFFICE.

DWIGHT T. SCOTT, OF WASHINGTON, DISTRICT OF COLUMBIA.

DESIGN FOR A CHECK.

52,753.

Specification for Design.

Patented Dec. 10, 1918.

Application filed June 12, 1916. Serial No. 103,329. Term of patent 3½ years.

To all whom it may concern:

Be it known that I, DWIGHT T. SCOTT, a citizen of the United States, residing in the city of Washington, District of Columbia, have invented a new, original, and ornamental Design for a Check, of which the following is a specification, reference being had to the accompanying drawing, forming a part thereof.

The figure is a view of a check on which my new design is shown.

I claim:—

The ornamental design for a check, as shown.

DWIGHT T. SCOTT.

Witnesses:

BENNETT S. JONES,
H. O. GORDON.
